(57) CLAIM

The ornamental design for a lighter sleeve, as shown and described.

DESCRIPTION

FIG. 1 is a side perspective view of a lighter sleeve showing my new design;

FIG. 2 is a front view thereof;

FIG. 3 is a back view thereof;

FIG. 4 is a top view thereof; and,

FIG. 5 is a side view thereof.

The broken lines in the drawings depict parts of the lighter sleeve that form no part of the claimed design.
